UNITED STATES PATENT OFFICE.

ELLIS W. TEST, OF MICHIGAN CITY, INDIANA.

SHEET-METAL CAR END.

1,406,701.

Specification of Letters Patent. Patented Feb. 14, 1922.

Application filed August 8, 1921. Serial No. 490,576.

To all whom it may concern:

Be it known that I, ELLIS W. TEST, a citizen of the United States, and resident of Michigan City, county of La Porte, and

5 State of Indiana, have invented certain new and useful Improvements in Sheet-Metal Car Ends, of which the following is a specification, and which are illustrated in the accompanying drawings, forming a part

10 thereof.

The invention relates to car ends formed of sheet metal, the plate or plates of which the end is formed being stiffened and strengthened by corrugations.

15 The object of the invention is to increase the stiffness and strength of such plates by an improved form and arrangement of corrugations; and it consists in a structure such as is hereinafter described, and as illustrated in the accompanying drawings, in which—

Fig. 1 is a detail side elevation of a box car provided with the improved end;

Fig. 2 is an end elevation thereof;

25 Figs. 3, 4 and 5 are detail sections, respectively, on the lines 3—3, 4—4 and 5—5 of Fig. 2.

The invention is illustrated in connection with a box car, and because of the height of the car two end plates 10 and 11, of substantially identical form, are employed, the upper plate overlapping the upper margin of the lower plate, as shown.

30 The two plates being substantially identical in form, but one need be specifically described.

The plate, as 11, is provided by pressing with an outward central bulge 12, which, because the length of the plate exceeds its width, is preferably oval in contour. At each of its ends the bulge 12 merges into a plurality of depressions, as 13, 14, 15, 16, formed by pressing the plate inwardly, these depressions extending longitudinally of the

45 plate to within a short distance of its end. The depressions 13 to 16, with the intervening portions 17, 18 and 19 of the plate, which remain in its original plane, form a series of short corrugations.

50 The marginal portions of the plate remain in its original plane, and may be flanged inwardly, as shown at 20 and 21, for attach-

ment to the framing of a car, the flange 21 across the top of the plate 11 serving to carry a nailing strip when an inside lining 55 for the car is employed.

The bulge 12 forms an arch, curving in all directions, its longer dimension springing from the bottoms of the depressions 13 to 16 and from the intermediate portions of the 60 plate 17, 18 and 19. Because of the end corrugations this arch is of the height found desirable in practice, with a minimum projection beyond the plane of the plate, thus reducing the length of the car through its ends 65 and not encroaching upon the space necessary for the end accessories of the car.

A plate of the configuration described possesses great strength to resist the pressure of shifting lading. Pressure from within on 70 the central portion of the plate is distributed in all directions toward its margin, and is resisted largely by the tensile strength of the metal. The end corrugations prevent the bending of the plate under outward stresses, 75 and, by shortening the arch of the central bulge, increase its strength.

While the depressions 13 to 16 are shown as of greater width than the intervening portions of the plate which remain in its original plane, the particular size and configuration of these depressions may be varied without departing from the scope of the invention.

I claim as my invention—

1. A car end comprising a sheet metal plate having flat marginal portions and a central outward bulge, and a plurality of longitudinally disposed inwardly extending corrugations in its flat portions and merging into the bulge. 85

2. A car end comprising a sheet metal plate having flat marginal portions, a central outward bulge, and a series of inwardly projecting corrugations between its flat marginal portions and the bulge and merging into the latter. 95

3. A car end comprising a sheet metal plate having flat marginal portions, a central oval outward bulge, and a series of inwardly projecting corrugations between the flat marginal portions of the plate and the ends of the bulge and merging into the latter. 100

4. A car end comprising a sheet metal plate having flat marginal portions, a central outward bulge, and a series of inwardly projecting corrugations between the flat marginal portions of the plate and the ends of the bulge and merging into the latter.
5. A car end comprising a sheet metal plate

having flat top, bottom and side marginal portions and a central outward bulge, and a plurality of longitudinally disposed inwardly extending corrugations in its flat side portions and merging into the bulge. 10

ELLIS W. TEST.
